UNITED STATES PATENT OFFICE.

JOHN S. STEWART, OF LOCKHART, ALABAMA.

SHIP-COALING DEVICE.

1,320,368.

Specification of Letters Patent. Patented Oct. 28, 1919.

Application filed May 18, 1916. Serial No. 98,395.

To all whom it may concern:

Be it known that I, JOHN S. STEWART, a citizen of the United States, and residing at Lockhart, in the county of Covington and 5 State of Alabama, have invented certain new and useful Improvements in Ship-Coaling Devices, of which the following is a specification.

The present invention relates to the class 10 of loading and unloading and has particular reference to new and useful improvements in ship-coaling devices.

The primary object of my invention is to provide new and useful improvements in 15 coaling devices for ships when at sea without the necessity of cable or other unreliable conveying apparatus between a collier or the like and a ship to be coaled.

Another object of my invention is to provide 20 a ship-coaling device of the class described which may be built in or permanently associated with a coal carrying vessel such as a barge or the like, the loading mechanism having suitable driving means 25 associated therewith which in the present instance is preferably an electrical motor.

A further object of my invention is to provide means carried on a coaling ship whereby the delivering vessel may be maintained 30 at a suitable safe distance from the receiving vessel at the same time affording quick transfer of the cargo with the least amount of weight.

Other objects and advantages to be derived 35 from the use of my improved coaling ship will appear from the following detailed description and the claim, taken with the inspection of the accompanying drawing, in which—

40 Figure 1 is a top plan view of my improved coaling ship and the coal conducting mechanism showing the same in operative position.

Fig. 2 is a longitudinal sectional view 45 taken on the line 2—2 of Fig. 1 looking in the direction of the arrows, and

Fig. 3 is a transverse sectional view taken on a line 3—3 of Fig. 1 looking in the direction of the arrows.

50 Referring more particularly to the drawings, wherein similar characters of reference designate like and corresponding parts throughout the various views, 1 designates the hull of my improved vessel having the usual bottom 2 and sides 3. The hull 1 is provided with fore and aft holds 4 and 5,

respectively. The vessel may be used as a barge or lighter for towing purposes or may be self-propelled, in which event the holds 4 and 5 may be employed for containing propelling machinery, crews' quarters, etc.

The hull of the vessel is provided with the usual weather deck 6, the forward portion of the weather deck being provided with a hatch 7, closed by a door 8, covered by a protecting grating 9. An upper deck 10 is arranged transversely of the vessel, preferably a little forward of the midship section and a platform 11 is supported thereabove, said platform and deck being strengthened by a block 12. The hoisting mechanism of my invention is carried on a pair of vertical standards 13 and 14 extending from the keel of the vessel to a suitable point above the platform 11 and connected by means of a brace 75 or strengthening beam 15.

The coal delivering mechanism of my invention includes an endless conveyer 16 of the bucket type comprising a pair of chains 17 and a plurality of buckets or the like 18 80 pivotally carried thereby as indicated at 19.

The chains 17 are trained about a plurality of sets of sprocket wheels 21, 22, 23 and 24 mounted on shafts 25. The standards 13 and 14 are provided with suitable openings 85 26 for accommodating the bucket, sprocket and chain, said standards forming bearings for said shaft 25.

I provide driving means for the conveyer 16, said means in the present instance comprising an electric motor 27 the armature shaft of which is extended as at 28, mounted in a bearing 29 and having a pinion 30 thereon for engagement with one of the chains 17 of said conveyer. In order to equalize the 95 drive on the conveyer 16 I provide a countershaft 31 mounted in a bearing 32 and having pinions 33 on its free ends for engagement with the first mentioned pinions 30 and a pinion 34 carried by a stub-shaft 35 100 mounted in a bearing 36, the last mentioned pinion being in engagement with the other chain of the conveyer 16.

I provide a coal containing hopper or the like which is preferably located aft of the 105 conveyer mechanism hereinbefore described, said hopper being designated 37 and having an inclined bottom wall 38, the inclination of the bottom 38 being forwardly of the vessel. A plurality of openings 39 are provided in the bottom 38, said openings being normally closed by sliding doors 40. A

lever mechanism 41 is provided for opening and closing said sliding doors. A protecting grating 42 is preferably arranged above the opening for an obvious purpose.

5 It will be readily apparent from an inspection of Fig. 2 that the buckets 18 pass through a suitable opening 43 provided in the bottom wall 38 of the hopper 37. In order to convey the contents of the hopper 10 37 to the buckets, I provide a conveyer, preferably of the endless type, designated 44 and being trained over rolls 45 and 46 mounted in a suitable frame 47 beneath the openings 39 hereinbefore referred to. The 15 conveyer 44 ends at a point proximate to the path of travel of the buckets 18 whereby to convey the contents of the hopper 37 to said buckets as desired.

Necessarily, the conveyer 44 must have 20 some driving means and I therefor provide the driving chain 48 trained over a sprocket 49 operatively associated with the rollers 45. said chain being further trained over an idler 50 carried by one of the standards, 25 and thence over a power receiving sprocket 51 carried by the same standard, in the present instance the standard 14. In order to drive the sprockets 51, I provide a pinion 52 mounted on the shaft 53 and rotatable with the said sprockets, said pinion 52 meshing with a relatively large gear 54 carried on one of the shafts 25, the shaft being lengthened for this purpose. A bearing bracket 55 is provided for the shaft 53 and the extended portion of one of the shafts 25.

30 I provide a coal deck 56 having outwardly inclined portions 57, which portions are provided with coal directing flanges 58, whereby to convey the coal to the delivery 40 chutes 59, arranged in a novel mounting hereinafter described.

I provide means for emptying the buckets 18 automatically as the same reach a predetermined point on the coal deck, said means 45 preferably embodying a trip member 60 pivoted at 61 in a bracket 62 mounted on the coal deck. A coil spring or the like 63 serves to normally tend to maintain the trip 60 in the lower position, a set screw 64 50 serving to adjust said trip to the desired height. The conveyer preferably travels in the direction indicated by the arrow in Fig. 2, and it will be seen as the buckets pass the trip the former are tilted as indicated to advantage in Fig. 2 emptying the contents thereof on to the coal deck and thence to the chutes.

55 In the present instance, I have shown in Fig. 1 two receiving vessels designated 65 and 66, said vessels having the usual hatches 67 forming the entrances to the coal bunkers. In order to adjust the chutes 59 to the desired height, I provide brackets 68

carried by the upper ends thereof. The 65 brackets 68 are formed to provide rack bars 69 arranged in meshing engagement with pinions 70 carried on brackets 71 mounted on the deck 10. Cranks 72 carried with the 70 pinions serve to rotate the latter for raising and lowering the chute. I do not limit myself to the showing disclosed in the drawing in so far as the chute construction and adjustment is concerned, but I do lay particular stress upon the novel receiving and conveying mechanism as well as the arrangement of the conveyer 44 in the hopper 37. 75

In order to prevent contact between the collier and the vessels to be coaled I provide fenders 73 mounted as at 74 on the sides of the collier, said fenders being adjustable in height by means of cables 75 framed over drums 76 operable by cranks 77.

80 From the above description taken in connection with the accompanying drawings, it is thought that a clear and comprehensive understanding of the construction, operation and advantages of my invention may be had, and while I have shown and described my invention as embodying a specific structure, I desire that it be understood 85 that I may make such changes on said structures as do not depart from the spirit and scope of the invention as described.

85 What I claim as new and desire to secure by Letters Patent is:—

90 A loading device of the character described, comprising in combination with a ship having its deck inclined and formed with a series of discharge openings, of 95 doors for normally closing said discharge openings, inclined conveying means arranged beneath said openings and extending longitudinally of said inclined portion of the deck, vertically disposed conveying means including a series of buckets 100 communicating with the hull of the ship and having a horizontally disposed stretch at a point above the deck, said vertically disposed conveying means communicating with the inclined conveying means whereby 105 to permit the discharge of matter from the inclined conveying means thereinto, means in the path of the buckets on the horizontal stretch of said conveying means for tripping the buckets at a predetermined point 110 and causing the dumping of the contents thereof, laterally inclined chutes arranged on the ship at opposite sides of the horizontal stretch of the vertically disposed conveying means, and means for vertically adjusting the chutes independently of each other.

115 In testimony whereof I affix my signature hereto.

120 JOHN S. STEWART.
